APPARATUS FOR REFORMING THERMO-PLASTIC SHEETS

Earl F. Middleton, New Rochelle, and
Carl W. Middleton, Larchmont, N. Y.

Application October 2, 1946, Serial No. 704,406

3 Claims. (Cl. 18—19)

1

The invention herein disclosed relates to reforming sheets of thermo-plastic material; more particularly, the invention relates to forming a bead on the edge of a sheet of thermo-plastic material and the forming of various articles therefrom.

Heretofore, and prior to the invention herein disclosed, beads have been formed on the edge of sheets of thermo-plastic material and such sheets with the beads thereon have been shaped to form the side walls of boxes, such for example as hat boxes. However, as heretofore effected, the bead formed has been tangential to the plane of the sheet. When such sheets with such a bead thereon are shaped to form the side wall of a box, the bottom of the box merely rests upon the bead, and must be cemented thereto. Such box constructions are expensive and are not entirely satisfactory as they lack rigidity and the cementing of the bottom to the bead is not, generally, satisfactory or permanent.

By the invention herein disclosed, a bead is so formed at the edge of a sheet of thermo-plastic material that it is off-set from the tangential relation to the plane of the sheet in such manner as to form a groove or recess between the bead and the plane of the sheet. When such a sheet is shaped to form the side wall of a box, a round hat box, for example, the recess is of slightly greater diameter than the wall of the box and the mean diameter of the bead is substantially the same as the diameter of the side wall of the box. A bottom is readily snapped or pressed into the recess and a rigid, permanent construction is obtained without cementing or otherwise securing the bottom to the bead.

A machine, forming a part of the invention and a hat box also forming part of the invention and illustrating preferred embodiments of the invention are illustrated in the accompanying drawings and described in detail below, from which description a clearer understanding of the invention may be had.

The drawings include:

Fig. 1 which is a plan of a machine, embodying the invention, for forming beads on opposite edges of a sheet of thermo-plastic material;

Fig. 2 which is a longitudinal, sectional elevation of the same taken on the line 2—2 of Fig. 1;

Fig. 3 which is an enlarged, fragmentary plan of the same taken on the line 3—3 of Fig. 2;

Fig. 4 which is a fragmentary elevation illustrating certain details of the drive mechanism;

Fig. 5 which is a transverse, sectional elevation taken on the line 5—5 of Fig. 3;

2

Fig. 6 which is an enlarged, transverse, sectional elevation taken on the irregular line 6—6 of Fig. 2;

Fig. 7 which is an enlarged, fragmentary elevation, partly in section of the carrier for carrying a sheet through the machine in fixed relation to a bead-forming die;

Fig. 8 which is an enlarged, fragmentary, sectional plan of a bead-forming die taken on the line 8—8 of Fig. 6;

Fig. 9 which is side elevation of the same taken on the line 9—9 of Fig. 8;

Figs. 10, 11, 12, 13 and 14 which are longitudinally spaced, in progressive relation to the movement of a sheet through the die, transverse sectional elevations of the bead-forming die, taken respectively on the lines 10—10, 11—11, 12—12, 13—13 and 14—14 of Fig. 8;

Fig. 15 which is an enlarged, fragmentary, sectional plan of the opposite die, taken on the line 15—15 of Fig. 6;

Fig. 16 which is a side elevation of the same taken on the line 16—16 of Fig. 15;

Figs. 17, 18 and 19 which are longitudinally spaced, transverse, sectional elevations of the same taken respectively, on the lines 17—17, 18—18, and 19—19 of Fig. 15;

Fig. 20 which is a fragmentary, sectional plan, similar to Figs. 8 and 15 of an alternative form of bead-forming die especially adapted for forming a square bead;

Figs. 21, 22 and 23 which are longitudinally spaced, transverse, sectional elevations of the same taken, respectively, on lines 21—21, 22—22 and 23—23 of Fig. 20;

Fig. 24 which is a diametrical, sectional elevation of a box formed in accordance with and embodying the invention;

Fig. 25 which is a similar, fragmentary, sectional elevation of an alternative form; and

Fig. 26 which is a like, fragmentary, sectional elevation of another alternative form.

The machine illustrated in the accompanying drawing is especially adapted for forming beads on both edges of a continuously moving web or sheet of thermo-plastic material, such, for example as cellulose acetate and like thermo-plastic sheets. All of the mechanism (Figs. 1, 2 and 6) may be, and is with the exception of the driving motor, mounted upon a frame, designated generally by the character A. At one end of the frame there is a support B for a roll of thermo-plastic, sheet material C. Proceeding in accordance with the movement of a web of material through the machine, from right to left as seen

in Figs. 1 and 2, the machine includes straightening or stress-relieving mechanism D for relieving any tension or stresses in the web which are likely to cause crinkling or unevenness in the web; carrier means E for carrying the web through a bead-forming section F is fixed and constant relation to the dies G and H; and shaping means I for shaping, in this instance, the web into cylindrical form. The carrier means E moves the web continuously, drawing it from the roll C and through the stress-relieving mechanism D. From the stress-relieving mechanism the carrier moves the web, positively and in fixed relation to the dies G and H, through the bead-forming section F and delivers or pushes the web, with beads formed on both edges, to the shaping means I. Here, an operator severs the web at spaced intervals to produce a continuous series of cylinders, each having beads formed at both edges.

The frame A of the particular machine illustrated in the drawings includes two, transversely spaced supports 1 and 2, supported in turn by uprights or standards, such as the uprights 1a and 1b of the support 1. In bearing brackets, hereinafter designated and described, secured on these supports, the various shafts of the machine are journaled. The supports are spaced apart a distance such as to accommodate the greatest width of web which it may be desired to operate. The dies G and the adjacent part of the carrier mechanism E are adjustably mounted on cross beams 3 and 4 extending between and secured to the supports 1 and 2. These cross beams 3 and 4 have T-slots therein, and support brackets 5 and 6, respectively. The brackets 5 and 6 are attached to a sub-frame support 7 on which the die G and adjacent portion of the carrier means E are mounted. The brackets 5 and 6 are secured to, in any adjusted position, the cross beams 3 and 4 by bolts, the heads of which are engaged in the T-slots of the cross beams and nuts 8 and 9, and 10 and 11 respectively.

At one end of the frame, to the right as seen in Figs. 1 and 2, there are provided bearing brackets 12 and 13, mounted respectively on the supports 1 and 2. These bearing brackets 12 and 13 have slots 14 and 15, inclined to the horizontal, to receive the reduced ends 16 and 17 of a spindle 18 upon which a roll or spool C is mounted and to which the roll is fixedly secured. The bearing brackets 12 and 13 form journals for the spindle 18. A tensioning device, in the form of a Prony brake, is associated with the spindle to prevent free rotation of the roll C. This consists of a brake drum 19 (Figs. 1 and 2) fixed to the spindle 18 by a set screw 20, and a brake band 21. The brake band is fixed at one end to a fixed rod 22, passes over the brake drum 19 and has weight 23 attached to the other or free end.

The stress-relieving mechanism D consists of a series of tension rollers and means for heating the web as it passes about the rollers. Alternate rollers are at different elevations. Proceeding in the direction of the movement of the web, from right to left (Figs. 1 and 2), there are a roller 24 over which the web passes, a roller 25 below the level of the roller 24 and under which the web passes, a roller 26 at the level of the roller 24 and over which the web passes, a roller 27 at the level of the roller 25 and under which the web passes, a roller 28 at the level of the roller 24, a roller 29 at the level of the roller 25, and a roller 30 below and cooperating with the roller 29. The roller 30 is so positioned with respect to the roller 29 that the web passes between them and is

finally sized and straightened in the manner of the action of a calender. The axis of the roll 30 is also slightly advanced, relative to the direction of the movement of the web, with respect to the roller 29 and so acts to support the web as it passes to the carrier means E.

The rollers 24 to 30 inclusive are of such length as to span the distance between the frame supports 1 and 2. Conveniently, they are all journaled, at one end, in a bearing bracket 31 mounted on the support 1 and at the other end in a bearing bracket 32 mounted on the support 2. Each roller carries an adjustable collar, 24a, 25a, 26a, 27a, 28a, 29a, and 30a respectively, which are adjusted on the rollers to the width of the web passing through the machine. The collars, in effect form edge guides, contacting and guiding the edge of the web.

Beneath (Fig. 2) the rollers 24 to 30 inclusive 20 there is provided means for heating the web as it passes over and under the rollers. In the particular machine illustrated in the drawings, the heating means consists of a plurality of infrared heating units 33 mounted on a support 34 and distributed to provide a uniform heating of the web 25 passing thereover. With a positive pull on the web by the carrier means E, as will hereinafter be described, against the tension of the Prony 30 brake device associated with the spindle 18, the web is under tension as it passes about the rollers 24 to 30. In passing about the rollers, under such tension it is uniformly heated by the heating units 33. All internal and locked-in stresses are thus 35 relieved and the web passes to the carrier means and bead-forming dies with uniform stresses throughout and without any tendency to crinkle or wrinkle because of uneven pressure due to non-uniform or locked-in stresses and strains.

The carrier means E constitutes the driving 40 means for moving the web, and also the means for fixedly positioning the web with respect to the dies G and H of the bead-forming section of the machine as the edges of the web pass through the bead-forming dies. The carrier means primarily 45 consists of opposed, endless chain grippers. As seen in Figs. 1, 2, 4 and 5, a drive shaft 35 is journaled at one end in a bearing bracket 36 (Figs. 3 and 5) fixedly secured on and supported by the support 2. At the other end, the shaft 35 is journaled in an upright bearing bracket 37 (Figs. 3 and 5) adjustably mounted on the cross member 3. The shaft 35 extends through both bearing brackets 36 and 37 and it is splined as at 38 and 39 (Fig. 5). On one end 50 of the shaft 35, that extending through the bearing bracket 36 (to the right as seen in Fig. 5), there is secured, for rotation therewith, a drive pulley 40. Between the drive pulley 40 and the bracket 36 there are secured to the shaft 35, a sprocket 41 and a gear 42. Between the bearing 55 brackets 36 and 37 and adjacent the bracket 36, there is fixed to the shaft 35 a carrier-chain sprocket 43, and adjacent the bracket 37, splined to the shaft 35 but movable with the bracket 37, there is mounted on the shaft 35 a carrier-chain sprocket 44.

A belt 45 (Figs. 1, 3 and 5) engages drive pulley 40 and a pulley 46 mounted on a cross shaft 41. On the opposite end of the shaft 47, there is fixed 60 to the shaft another pulley 48. A belt 49 engages the pulley 48 and an adjustable, cone pulley 50 mounted on the shaft of an electric motor 51. The cone pulley 50 is adjustable through a hand wheel 52 (Fig. 1) and the arrangement of the pulleys 48 and 50 and the belt 49, constitutes

a variable speed drive well known in the art as a "Reeves drive." Through this train of pulleys, belts and shafts, the shaft 35 is driven at adjustable speed by the electric motor 51.

Also extending through and journaled in the bearing brackets 36 and 37, there is, above the shaft 35, a shaft 53. This shaft is splined, or has diametrically opposite key ways as at 54 and 55. On the end of the shaft outside of the bracket 36 (to the right as seen in Fig. 5), there is fixed on the shaft 53 a sprocket 56. Between the sprocket 56 and the bracket 36, there is fixed to the shaft 53 a gear 57 which meshes with the gear 42. On the opposite side of the bracket 36, there is fixed to the shaft 53 a carrier-chain sprocket 58. A similar carrier-chain sprocket 59 is splined or keyed to the shaft 53 adjacent to the bracket 37 and in line with the carrier-chain sprocket 44. The sprocket 59 is, as is also the sprocket 44, movable and adjustable with the bracket 37.

Adjacent the roller 30 of the stress-relieving mechanism D there are (Figs. 1 and 3) four stub shafts, 60, 61, 62, and 63. The stub shafts 60 and 61 are secured in a pair of brackets 64a and 64b (adjustable longitudinally of the machine) mounted upon the sub-frame support 7. The stub shafts 62 and 63 are secured in a like pair, brackets 65a and 65b, adjustable longitudinally of the machine, mounted on the frame support 2. On the shaft 60, inside the bracket 64, there is loosely mounted a carrier-chain sprocket 66 (Figs. 2 and 4), and on the shaft 61, there is loosely mounted a carrier-chain sprocket 67. In like positions, there are mounted on the stub shafts 62 and 63, respectively, carrier-chain sprockets 68 and 69.

The carrier-chain sprockets carry opposed, endless carrier-chains which are especially constructed and arranged to firmly grip the web and carry it through the bead-forming section F of the machine. To this end, an endless carrier-chain 70 extends over, and engages the sprockets 59 and 66. A similar, endless carrier-chain 71 extends over the sprocket 44 and 67. In like manner, opposed, endless carrier-chains 72 and 73 (Fig. 6) extend over, respectively, sprockets 58 (Fig. 5) and 68 (Fig. 1), and 43 and 69.

The details of the carrier-chain construction are shown in Fig. 7. Each carrier-chain consists of a series of flexibly connected links 74. Each link includes a channel-shaped member 75 (Figs. 6 and 7) between the flanges of which channel-shaped member two spaced shafts 76 and 77 extend. These shafts are fixed with respect to the channel-shaped member. On each of the shafts 76 and 77 of each link, there is rotatably mounted a substantially V-shaped idler 78. The chain links, so formed, are connected together in an endless chain by straight links 79 extending between adjacent shafts of the successive carrier links. On the web portion of the channel-shaped members of the carrier links, there may be rubber-like deposits 80 which, when opposed carrier-chains are forced together, grips a sheet therebetween in such manner as to prevent any slippage. A properly machined surface on the webs will also grip the sheet in such manner as to prevent slippage.

These carrier chains grip a web of thermoplastic material, draw it off the roll C, through the stress-relieving mechanism, carry it through the bead-forming section F, and deliver it to the shaping mechanism I. The bead-forming dies G and H are between the ends of the carrier-chains. In drawing the thermo-plastic web or

sheet through the bead-forming section F, it is important that the carrier, having received a stress-relieved sheet or web from the stress-relieving mechanism, does not permit any slippage. It should hold, and carry, both edges of the web at a particular, predetermined distance from the adjacent side wall of the bead-forming dies. To this end, the opposed carrier-chains are caused to grip the sheet with a positive grip within one-sixteenth of an inch of the adjacent side wall of the bead-forming die.

By adjusting the brackets 64a, 64b and 65a, 65b, the proper or desired tension may be secured on the carrier-chains. For effecting a positive grip upon the web by cooperating carrier chains, tracks are provided which position the opposed carrier-chains in gripping relation adjacent the dies. A track 80, having a substantially V-shaped end section 81, complementary to the V-shape of the idlers 78, supports the chain 71 so that as it passes the die G, it forms a rigid continuous gripper. The track 80' is mounted on a member 82 that is fixed with respect to the frame by screws 83.

The upper carrier chain 70, that cooperates with the chain 71, is resiliently urged into gripping relation with the chain 73 by a resiliently mounted track 84. The track 84 has a V-shaped end section 85 that engages the rollers 78 of the chain 70. This track 84 is secured, as by machine screws 86, to a vertically movable member or bar 87 which is held to the frame by a member 88 that engages the side wall of bar 87. The member 88 is secured in place by machine screws 89 which extend through enlarged openings (such as the opening 90, Fig. 6) and are threaded into the member 88. Ferrules, such as the ferrule 91, act as spacers to prevent tightening of the screws 89 to such an extent as to bind the member or bar 87. At spaced intervals compression springs, such as the spring 92, act upon the bar 87 urging it downward in a direction to cause the track 84 to resiliently urge the chain 70 into contact with the chain 71. One end of the spring 92, rests upon the bar 87 and the upper end is engaged by a movable abutment 93. A set screw 94, threaded through a plate 95, engages the abutment 93. Through this set screw the force exerted by the spring 92 on the bar 87 may be adjusted. In like manner, the chains 72 and 73 are urged into gripping relation by a fixed track 96 supporting the chain 73 and a movable resiliently urged track 97 engaging the chain 72.

The die G consists of an elongated metal block or mold 98 having a forming cavity 99 extending longitudinally thereof and a slot 100 extending through a side wall 101 and in communication with the cavity 99. In an opening formed in the mold 98, there is inserted an electrical heating element 102 which maintains the mold at the desired temperature during operation of the machine. The mold is positioned on the machine with the slot 100 at the plane of the engagement of the carrier-chains 70 and 71 and with the side wall 101 thereof adjacent to, spaced approximately one sixteenth of an inch from, the edge or sides of the cooperating or engaging sections of the carrier-chains.

The forming cavity 99 (Figs. 8 to 14 inclusive) is circular in cross section to form a circular bead and extends longitudinally through the mold. For a portion of the length of the mold, from the entering end 103 to a point or plane 104, the forming cavity is inclined to the side wall 101 of the mold. From the plane 104 to a plane 105, the

cavity is substantially parallel to the side wall 101, and from the plane 105 to a plane 106, the cavity is inclined both to the wall 101 and to the adjacent bottom wall 107 of the mold. Also, from the plane 105 to the plane 106, a portion of the slot 100, gradually and progressively inclines toward the wall 107 to form an off-set 108. From the plane 106 to the end of the mold, the cavity and slot remains the same and are substantially parallel to the side walls 101 and 107.

In the portion of the mold cavity from the entering end 103 to a point somewhat beyond the plane 104, there is a fixed mandrel 109. The mandrel is of such diameter that with the wall of the cavity 99, an annular cavity is formed of a width substantially equal to the thickness of the sheet to be acted upon. The mandrel has formed thereon a boss 110 which fits snugly within the cavity to position the mandrel therein, and a head 111 which engages the end wall 103 of the mold.

In operation, the mold is heated to soften the edge portion of a plastic sheet passing through the mold. The edge portion of a thermo-plastic sheet or web 112 is entered in the slot 100 at the entering end 103 of the mold. The web is carried through, with the edge portion in fixed relation to the mold, by the carrier means described above. As it moves through the portion of the mold between the end 103 and the plane 104, the edge portion of the sheet, because of the inclination of the cavity towards the wall 101, is forced around the mandrel 109, until at the plane 104, a circular bead 113 is formed on the edge of the web. In passing through the section between the planes 104 and 105, the bead 113, so formed, is set. On moving through the section between the planes 105 and 106, the bead is offset so that its axis is contained in the plane of the web and a recess 114 is formed between the bead and the plane of the web.

The die H (Figs. 15 to 19) is similar in construction to the die G, except for the nature of the forming cavity. This die consists of a metal block or mold 115 having a forming cavity 116, circular in cross section, extending longitudinally therethrough. A slot 117 extends through the side wall 118 thereof and communicates with the cavity 116. An electrical heating element 119 is received within an opening in the mold, extends longitudinally thereof and serves to heat the mold.

The cavity in the mold 115 is arranged to form a bead 120 (Fig. 19) on the other edge of the web 112. The bead 120 is circular in form and positioned without any offset, with the axis thereof within the plane of the web. To form such a bead, the cavity 116, is, from the entering end 121 of the mold, inclined to the side 118 of the mold to a point or plane 122. From the plane 122 to the opposite end of the mold, the cavity extends parallel to the side 118 of the mold. However, from a plane 123 to a plane 124, the cavity inclines to the adjacent bottom wall 125 of the mold. A fixed mandrel 126 similar to the mandrel 109, extends into the cavity to a point somewhat beyond the plane 122. Thus, the edge of the sheet enters the cavity tangentially, and in passing to the plane 122, it winds about the mandrel to form the bead. Thereafter, in passing from the plane 122 to the plane 123, the bead is set, and in passing to the plane 124, the bead is shifted to bring the axis thereof into the plane of the web.

In Figs. 20 to 23 inclusive a mold or die 125 is illustrated by which a bead 126, square in cross

section, may be formed. This die also has a longitudinal forming cavity 127 therethrough and a longitudinal slot 127a. From the entering end 128 thereof to a point or plane 129, the cavity is circular in cross section and converges toward the side wall 130 thereof. In this portion there is a round mandrel 131 about which the bead is formed. From the point 129, to the end of the die, the cavity is substantially parallel to the side wall 130. The mandrel 131 extends part way into this parallel section of the cavity. Just beyond the end of the mandrel 131, the cavity gradually changes to square in cross section. In this last section of the cavity, there is a square mandrel 132 having a tapered end section 133. This mandrel is held in place by a longitudinal strip 134, extending from a corner of the mandrel and out through the side of the die at the slot 127a, which is widened at this section. The strip 134 has a flange 135 thereon which is secured to the wall 130 of the die. With this arrangement, the mandrel 132 may be said to float within the cavity and the bead formed can pass freely off the end of the mandrel.

From the bead-forming section F of the machine, the web passes (Figs. 1, 2 and 3) along a passage 136, provided with a cover plate 137 terminating in a partial cylindrical guide and guard 138. At the end of the passage 136, there are two pair of transversely spaced feed wheels 140, 141 and 142, 143. The feed wheels are located just inside of the beads formed on the web. Behind the feed wheels 140, 141 and 142, 143, there is an upwardly curved wall 144 having bead receiving channels 145 and 146 on each side thereof, which are attached to and constitute extensions of the mold cavities. As the heated web is forced along this wall, it curves with the wall 144 into cylindrical form, the end engaging the guide 138. When a cylindrical section is thus formed it is broken from the web by an operator. Thus, successive cylinders, having beads at each edge, as above described are formed. A heating element 136a is provided below the passage 136.

The feed wheels 140 and 142 are mounted upon a shaft 147 that is journaled at one end in a fixed bracket 148 extending from the frame, and a bracket 149 secured to the movable frame element 1. The wheel 142 is fixed to the shaft 147 and the wheel 140 is splined on the shaft. In like manner, the wheels 141 and 143 are mounted on a shaft 150 journaled in the lower brackets 148a and 149a, the wheel 143 being fixed to the shaft and the wheel 141 being splined on the shaft. The shaft 147 is driven by a chain 151 engaging a sprocket fixed on the shaft 53 and a sprocket 152 fixed on the shaft 147. The shaft 150 is also driven by a chain 153 which engages a sprocket 154 fixed on the shaft 35 and a sprocket 155 fixed on the shaft 150.

Various forms of beads may be formed on the edges of the web for different constructions. In Fig. 24, there is shown a cylindrical box having beads thereon as formed in the machine illustrated in the drawing and described above. In this construction, one bead 156 is formed and offset to form a recess 157, as described above. A flexible bottom 158, such as a card board, plastic or metal bottom, is snapped into the recess and forms with the cylinder a rigid box construction.

In Fig. 25, an inwardly extending offset 159, spaced from a bead 160, is illustrated. The bottom 161 is received between the offset 159 and the bead 160. Fig. 26 illustrates a construction

in which the square bead, above described, is utilized. In this construction, a bottom 162 is provided with a downwardly and inwardly extending, circumambient flange 163 which engages in the square bead.

In making cylindrical hat boxes, a web of thermo-plastic material is fed to the machine and acted upon as above described. However, before the web is fed to the machine it is scored transversely at spaced intervals, as at 165 (Fig. 3), and partially cut in from each edge as at 166 and 167. The distance between score lines is equal to the circumference of the box to be formed, plus a slight overlap. The scoring facilities severing the web into successive cylinders. Each such cylinder is cemented or welded at the overlap and the bottom is then inserted.

It will be obvious that various changes may be made by those skilled in the art in the details of the structures and the procedure described above within the principle and scope of the invention as expressed in the appended claims.

We claim:

1. In a machine of the kind described for forming the edge of a sheet of thermo-plastic material, stress-relieving means including a series of vertically and horizontally spaced rollers and a pair of opposed rollers, the lower roller of such pair of opposed rollers being in advance of the upper roller, opposed pairs of movable grippers in advance of the opposed rollers for gripping the sheet adjacent the longitudinal edges thereof and drawing the sheet in flat-wise relation from the opposed rollers, means for maintaining the sheet under tension, and means for heating the sheet as it passes over and under the vertically and horizontally spaced rollers and between the opposed rollers.

2. In a machine of the kind described for forming the edge of a sheet of thermo-plastic material, the combination comprising a forming die and carrier means movable past the forming die to carry a sheet with the edge thereof extending into the forming die, said carrier means including two, opposed, continuous carrier chains, each chain comprising a series of gripper links flexibly connected together by straight links, and each gripper link including a channel-shaped member,

V-shaped idlers mounted between the flanges of the gripper link, and a gripper pad on the web of the gripper link, a fixed track extending along the length of the forming die and fixed with respect to the die for engaging in the V-shaped idlers to fixedly relate the gripping chain with respect to the die in two, right angular directions, a movable track, movable toward and away from the fixed track for engaging the other of said chains, and resilient means acting upon said movable track to urge the chain engaged thereby into gripping relation with the other chain.

3. In a machine of the kind described for forming the edge of a thermo-plastic material, a bead-forming die for forming a bead on the edge of a sheet of thermo-plastic material, means for conveying a sheet of thermo-plastic material past the forming die with the edge thereof extending into the forming die, and means for shaping the sheet into a cylinder including a cylindrically curved wall having a curled edge to receive the bead formed on the edge of the thermo-plastic sheet by the forming die.
